(57) **CLAIM**

The ornamental design for a bottle, as shown and described.

DESCRIPTION

FIG. 1 is a top, front right side perspective view of a bottle showing our new design;

FIG. 2 is a side elevation view thereof, the opposing side, front and rear elevation views being identical; and,
FIG. 3 is a top plan view thereof.

The broken lines in the drawings illustrate the portions of the bottle that form no part of the claim.
